MOUNTING SUPPORT FOR COMMUTATOR SEGMENT UNDERCUTTING AND TURNING DOWN ATTACHMENTS

Walter H. Rhindress, 94 West St., Braintree, Mass.

Filed Oct. 31, 1960, Ser. No. 62,681

Term of patent 14 years

(Cl. D55—1)

Fig. 1.

Fig. 2.

FIG. 1 is a front perspective view of a mounting support showing my new design, the dotted lines illustrating where the undercutting and turning down attachments are mounted; and

FIG. 2 is a rear perspective view thereof.

I claim:

The ornamental design for a mounting support for commutator segment undercutting and turning down attachments, substantially as shown and described.
